LASTING MACHINE

Charles Martin Bagshaw and Harold Lane,
Leicester, England, assignors to United Shoe
Machinery Corporation, Flemington, N. J., a
corporation of New Jersey

Application November 5, 1949, Serial No. 125,753
In Great Britain November 17, 1948

21 Claims. (Cl. 12—9)

1

This invention relates to lasting machines, and particularly to improvements in lasting machines of the general type disclosed in United States Letters Patent No. 2,411,827, issued on November 26, 1946 in the name of Joseph Fossa. It will be understood, however, that in certain aspects the invention is of broader scope and not limited to use in a lasting machine of the exact mechanical construction illustrated in that patent.

In the machine disclosed in the aforementioned patent, the stock to be lasted is tensioned, in different locations, successively along the edge of the shoe bottom, by means of a reciprocating gripper having jaws which seize the lasting margin of the stock and pull it in a direction substantially parallel to the bottom of the shoe and over in contact with a shoe-bottom-engaging member. This patented machine is provided with means, operable in time relation to the pulling action of the gripper, for pressing the lasting margin of the tensioned stock against the bottom of the shoe in a location closely adjacent to, but spaced lengthwise of the shoe from, the gripper, and this pressing means is adapted, while in pressing engagement with the lasting margin, to move in a direction to feed the shoe. During those intervals when the aforementioned pressing means is out of engagement with the lasting margin and while the gripper jaws are opened, the shoe is held against retrograde movement by a member which also applies additional pressure to the lasting margin.

Machines constructed in accordance with the disclosure of the above-mentioned patent have proved to be quite satisfactory and effective in operation, particularly for use in the lasting of the platform covers, or wrappers, of so-called slip-in lasted, or platform, shoes. However, it has been found that the operation of a lasting machine of this type may be considerably improved by a modification of the tensioning means, or reciprocating gripper. It is, therefore, an object of this invention to provide an improved lasting machine of the general type disclosed in the aforementioned patent. To this end, and in accordance with a feature of the invention, the herein illustrated machine is provided with a novel gripper-operating mechanism by means of which the gripper, as it is moved to pull the lasting margin of the stock over the bottom of the shoe and in contact with the shoe-bottom-engaging means, is caused to travel first in a path that is inclined upwardly, away from the bottom of the shoe, as well as inwardly from

2

the edge of the shoe bottom, and then in a path that is inclined downwardly toward the shoe bottom. Because of this upward movement of the gripper, a greater heightwise tensioning of the stock is obtained, while the lasting margin of the tensioned stock is eventually positioned close to the bottom of the shoe, and in a suitable location to be acted on by the pressing means, as a result of the subsequent downward movement of the gripper. The advantages of this improved gripper-operating mechanism are most apparent when the stock being lasted is unusually heavy and stiff, such stock being more difficult to tension properly in a direction heightwise of the last by a pull thereon directed only inwardly of the edge of the shoe bottom and in a path substantially parallel to the plane of the bottom of the shoe, and hence resistant to being pulled in over the bottom of the shoe and tensioned in a heightwise direction.

More particularly, cam-operated means are provided for causing the gripper to move in the aforementioned upwardly and downwardly inclined path and, in order to assure that the lasting margin of the stock will not escape from between the jaws of the gripper or that neither of the jaws will displace stock previously laid against the bottom of the shoe, means are provided for rendering the cam-operated means inoperative so that the gripper jaws return in a path that is substantially parallel, and close to the bottom of the shoe, in the same manner as in the machine of the above-mentioned patent. Preferably, and in the herein illustrated machine, the cam-operated means includes a cam that is yieldingly supported and a member carried by the pressing means is arranged to move this cam-operated means to an inoperative position.

The above objects and features of the invention will appear in the following detailed description of a preferred embodiment thereof, illustrated in the accompanying drawings, and will be pointed out in the claims.

In the drawings,

Fig. 1 is a view in side elevation showing certain of the operating parts of a machine of the type described in the aforementioned patent and illustrating the novel gripper-operating means of this invention;

Fig. 2 is a view in front elevation of the operating elements of the machine shown in Fig. 1;

Fig. 3 is a view in section, substantially on the line III—III of Fig. 1 and looking in the direction of the arrows, of a detail of construction; and

Fig. 4 is a view in side elevation and at an enlarged scale of a portion of the gripper-operating mechanism.

Referring to these drawings, the machine therein illustrated is, with the exception of the improved gripper-operating mechanism, of exactly the same construction as the machine illustrated in the aforementioned patent. For the purposes of simplicity, only as much of the patented machine as is necessary for an understanding of the present invention has been illustrated, it being understood that the aforementioned patent may be referred to for a description of those parts which have been omitted, or shown only in outline. To facilitate such reference and to permit a more ready understanding of the present invention, the parts of the herein illustrated machine which correspond to similar parts of the patented machine are identified with the same reference characters as were used in the aforementioned patent. Thus, the herein illustrated machine is shown as provided with a gripper having a rear jaw 10 and a front jaw 12, a shoe-bottom rest 14, a pressure-feed-foot 16, a feed-retaining member 18 and an edge guide roll 20. These instrumentalities are all mounted on, and operated by mechanism contained within, a hollow head construction 22 comprising upper and lower portions 24, 26 which are indicated in part by a broken line.

The rear gripper jaw 10 is attached, by means of a clamping bolt 30, to a carrier 32 which is supported, in a manner to be explained below, by two rocker arms 34, 36 which are journaled respectively on cross shafts 38, 40. These two rocker arms are oscillated, by means including a third rocker arm 46 and mechanism which is the same as that disclosed and described in the aforementioned patent, so as to reciprocate the carrier 32 and the jaw 10 which is carried thereby. The front jaw 12 is carried on the end of rod 102, which is slidably mounted on the carrier 32, and is urged toward engagement with a second rod 103 by means of a spring 150. The rod 103 is operated, in time relation to the reciprocating movements of a carrier 32, by mechanism not shown but which is identically the same as that described in the aforementioned patent, so as to cause the jaws 10 and 12 to seize the lasting margin of the stock being lasted and to pull it inwardly over and in contact with a shield portion 170 on the shoe-bottom rest 14 thereby to tension the stock in different locations successively along the edge of the bottom of the shoe, in the same general manner as is explained in said patent.

For the purposes of this invention, however, the gripper jaws 10 and 12, instead of pulling the stock in a direction substantially parallel to the bottom of the shoe, are caused to travel first in a path that is inclined upwardly, away from the bottom of the shoe, as well as inwardly from the edge of the shoe bottom, and then to travel in a path that is inclined downwardly toward the bottom of the shoe. These movements of the gripper jaws are effected in the following manner. The carrier 32 is pivotally mounted on the rocker arm 36 by means of a stud 44 and is connected to the rocker arm 34 so as to be movable heightwise thereof while still partaking of the oscillating movements of this rocker arm by means of the following arrangement.

A channel-like member 35 is secured to the upper end of the arm 34, as shown in Fig. 3. The carrier 32 is received by this channel-like mem-

ber and is secured thereto by means of a hemispherical member 39 which fits into a similarly shaped recess 33, formed in the carrier 32, and which has a rib 37 that projects into a slot 31 cut in one side of the member 35. A coil spring 29 is arranged so as to hold the carrier 32 yielding down against the bottom of the channel-like member, as shown in Figs. 1 and 3. The carrier 32 is swung about its pivotal connection to the arm 36, and against the resistance of the spring 29, so as to elevate and lower the gripper jaws, during movement of the carrier to the left, in Fig. 1, by the following mechanism.

A cam member 41, formed integrally with an arm 53, Figs. 1 and 4, is pivotally mounted, by means of a pin 55, on a face plate member 51 that is secured to the front of the frame portion 24 by means of a screw 59 and a shouldered stud 61, see Fig. 2. This cam member has two surfaces 43 and 45 which slope, respectively, upwardly and downwardly at an angle of about 30° to the horizontal. The stud 61 passes through a slot 63 in the arm 53 and a coil spring 65, anchored to a portion of the head part 24, normally holds the arm 53 and the cam member 41 formed thereon elevated to the position shown in Figs. 1, 2 and 4, as determined by the engagement of the stud 61 with the arm 53 at the bottom of the slot 63. Secured to the carrier 32, in a location adjacent to the cam member 41, is a second cam member 47 that is provided with two inclined surfaces 49, 51 which are complementary to the surfaces 43, 45 on the cam member 41.

During the movement of the carrier 32 and the jaw 10 to the left, Fig. 1, and just about at the time the lasting margin of the stock is gripped between this jaw and the front jaw 12, in the manner explained in the aforementioned patent, the surface 49 of the cam 47 comes into contact with the surface 43 on the cam 41. Thus, as the jaws 10 and 12 continue to move to the left and to pull the lasting margin of the stock inwardly over the bottom of the shoe and in contact with the shield portion 170 of the shoe-bottom rest 14, the surface 49 first rides up the surface 43 and then the surface 51 rides down the surface 45 and the jaws 10, 12 are correspondingly raised and lowered. Accordingly, after seizing the lasting margin of the stock, and during their pulling action, the gripper jaws are caused to travel first in a path that is inclined upwardly away from the bottom of the shoe, as well as inwardly from the edge of the shoe bottom, and then in a path that is inclined downwardly toward the bottom of the shoe while continuing their inward movement. By thus causing the gripper to pull in a direction that is inclined upwardly and away from the bottom of the shoe, a greater heightwise tensioning action is produced than could be obtained by a pull exerted in a direction parallel to the bottom of the shoe. At the same time, however, the subsequent movement of the gripper downwardly and toward the bottom of the shoe brings the lasting margin of the tensioned stock close to the shoe bottom and in a suitable position to be acted upon by the presser-feet-foot 16.

After the stock has been tensioned in the above manner, and prior to gripping another portion 70 of the lasting margin, the gripper jaws are preferably caused to travel in paths which are substantially parallel, and close to the bottom of the shoe in order that the lasting margin of the stock will not escape from between the gripper jaws and so as to avoid any tendency for either

of the jaws to displace stock that has already been laid against the bottom of the shoe. In the herein illustrated machine, this is accomplished by displacing the cam member 41 to an inoperative position during such further movements of the gripper jaws as occur prior to their gripping another portion of the lasting margin of the stock. As has been explained above, this cam member is formed on a pivoted arm 53 and is held in operative position by means of a coil spring 65. For depressing this arm, against the resistance of the spring, thus to lower the cam to a position in which it is inoperative to cooperate with the cam 47 to raise and lower the carrier 32, the following arrangement is provided.

The presser-feed-foot 16 is carried by an arm 242 which is moved up and down, in time relation to the operation of the gripper, by mechanism similar to that which is disclosed and described in the aforementioned patent. An abutment 67 is secured to the arm 242 and this abutment is so constructed and arranged as to depress the arm 53 just before the presser-feed-foot 16 reaches its lowermost position in contact with the shoe bottom. As is explained in said patent, see particularly Fig. 7 thereof, the presser-feed-foot remains in this position during the entire return movement of the rear jaw 10. The cam member 41 is thus moved down from operative position throughout the entire return movement of the rear jaw and the extent to which this cam member is depressed is such that the cam faces 43, 45 thereon are held out of contact with the cam faces 49, 51 on the cam member 47 and the rear jaw moves rearwardly in a direction substantially parallel to the bottom of the shoe. During such return movement of the rear jaw, the front portion of the slide 32 is held down in the channel member 35, with the rib 37 resting of the bottom of the slot 31, by the spring 29. However, at the beginning of the next forward movement of the slide 32, the presser-feed-foot is elevated and the abutment 67 moves upwardly away from the arm 53 so that the cam member 41 is returned, by the spring 65, to its operative position before the jaws 10, 12 close on another portion of the lasting margin and begin their pulling action. In Fig. 1 of the drawings, the parts are shown in the positions assumed during an early part of the forward movement of the carrier 32 and the presser-feed-foot has risen sufficiently to carry the abutment 67 out of contact with the arm 53.

With the exception of the improved gripper-operating mechanism which has been described above, the herein illustrated machine operates in generally the same manner as that of the aforementioned patent. Thus the lasting margin of the stock is pressed against the bottom of the shoe, and the shoe is fed along, by the action of the presser-feed-foot 16 while the shoe is held against retrograde movement during the back-feeding motions of the presser-feed-foot and while the gripper jaws are opened, by means of the feed retainer 18.

Having described the invention, what is claimed as new and is desired to be secured by Letters Patent of the United States is:

1. A lasting machine having, in combination, means for engaging the bottom of a shoe adjacent to the marginal edge thereof, a gripper for seizing the lasting margin of the stock to be lasted and for pulling said lasting margin inwardly over the bottom of the shoe and in contact with said

shoe-bottom-engaging means, thereby to tension the stock in a direction normal to the bottom of the shoe and to draw its lasting margin inwardly over the shoe bottom, and means for causing said gripper to move initially in a path that is inclined first upwardly, away from the bottom of the shoe, and thereafter downwardly toward the shoe bottom, to augment the tensioning action of the gripper and to position the lasting margin of the tensioned stock close to the bottom of the shoe.

2. A lasting machine having, in combination, means for engaging the bottom of a shoe adjacent to the marginal edge thereof, a gripper for seizing the lasting margin of the stock to be lasted and for pulling said lasting margin inwardly over the bottom of the shoe and in contact with said shoe-bottom-engaging means, thereby to tension the stock in a direction normal to the bottom of the shoe and to draw its lasting margin inwardly over the shoe bottom, and cam-operated means for causing said gripper to move initially in a path that is inclined first upwardly, away from the bottom of the shoe, and thereafter downwardly toward the shoe bottom, to augment the tensioning action of the gripper and to position the lasting margin of the tensioned stock close to the bottom of the shoe.

3. A lasting machine having, in combination, means for engaging the bottom of a shoe adjacent to the marginal edge thereof, a gripper for seizing the lasting margin of the stock to be lasted and for pulling said lasting margin inwardly over the bottom of the shoe and in contact with said shoe-bottom-engaging means, thereby to tension the stock in a direction normal to the bottom of the shoe and to draw its lasting margin inwardly over the shoe bottom, and means including a yieldably supported cam for causing said gripper to move in a path that is inclined first upwardly, away from the bottom of the shoe, and thereafter downwardly toward the shoe bottom, to augment the tensioning action of the gripper and to position the lasting margin of the tensioned stock close to the bottom of the shoe.

4. A lasting machine having, in combination, means for engaging the bottom of a shoe adjacent to the marginal edge thereof, a reciprocating gripper for seizing the lasting margin of the stock to be lasted and for pulling said lasting margin inwardly over the bottom of the shoe and in contact with said shoe-bottom-engaging means, during movement of said gripper in one direction, thereby to tension the stock in a direction normal to the bottom of the shoe and to draw its lasting margin inwardly over the shoe bottom, and means for causing said gripper to move initially in a path that is inclined first upwardly, away from the bottom of the shoe, and thereafter downwardly toward the shoe bottom, to augment the tensioning action of the gripper and to position the lasting margin of the tensioned stock close to the bottom of the shoe.

5. A lasting machine having, in combination, means for engaging the bottom of a shoe adjacent to the marginal edge thereof, a reciprocating gripper for seizing the lasting margin of the stock to be lasted and for pulling said lasting margin inwardly over the bottom of the shoe and in contact with said shoe-bottom-engaging means, during movement of said gripper in one direction, thereby to tension the stock in a direction normal to the bottom of the shoe and to draw its lasting margin inwardly over the shoe bottom, and cam-operated means for causing said gripper to move initially in a path that is inclined first

upwardly, away from the bottom of the shoe, and thereafter downwardly toward the shoe bottom, to augment the tensioning action of the gripper and to position the lasting margin of the tensioned stock close to the bottom of the shoe.

6. A lasting machine having, in combination, means for engaging the bottom of a shoe adjacent to the marginal edge thereof, a reciprocating gripper for seizing the lasting margin of the stock to be lasted and for pulling said lasting margin inwardly over the bottom of the shoe and in contact with said shoe-bottom-engaging means, during movement of said gripper in one direction, thereby to tension the stock in a direction normal to the bottom of the shoe and to draw its lasting margin inwardly over the shoe bottom, and means including a yieldably supported cam for causing said gripper to move in a path that is inclined first upwardly, away from the bottom of the shoe, and thereafter downwardly toward the shoe bottom, to augment the tensioning action of the gripper and to position the lasting margin of the tensioned stock close to the bottom of the shoe.

7. A lasting machine having, in combination, means for engaging the bottom of a shoe adjacent to the marginal edge thereof, a reciprocating gripper for seizing the lasting margin of the stock to be lasted and for pulling said lasting margin inwardly over the bottom of the shoe and in contact with said shoe-bottom-engaging means, during movement of said gripper in one direction, thereby to tension the stock in a direction normal to the bottom of the shoe and to draw its lasting margin inwardly over the shoe bottom, means operating in time relation to the pulling action of said gripper for pressing the lasting margin of the tensioned stock against the bottom of the shoe in a location closely adjacent to, but spaced lengthwise of the shoe from, said gripper, and means for causing said gripper to move initially in a path that is inclined first upwardly away from the bottom of the shoe, and thereafter downwardly toward the shoe bottom, to augment the tensioning action of the gripper and to position the lasting margin of the tensioned stock close to the bottom of the shoe.

8. A lasting machine having, in combination, means for engaging the bottom of a shoe adjacent to the marginal edge thereof, a reciprocating gripper for seizing the lasting margin of the stock to be lasted and for pulling said lasting margin inwardly over the bottom of the shoe and in contact with said shoe-bottom-engaging means, during movement of said gripper in one direction, thereby to tension the stock in a direction normal to the bottom of the shoe and to draw its lasting margin inwardly over the shoe bottom, means operating in time relation to the action of said gripper for pressing the lasting margin of the tensioned stock against the bottom of the shoe in a location closely adjacent to, but spaced lengthwise of the shoe from, said gripper, and cam-operated means for causing said grippers to move initially in a path that is inclined first upwardly, away from the bottom of the shoe, and thereafter downwardly toward the shoe bottom, to augment the tensioning action of the gripper and to position the lasting margin of the tensioned stock close to the bottom of the shoe.

9. A lasting machine having, in combination, means for engaging the bottom of a shoe adjacent to the marginal edge thereof, a reciprocating gripper for seizing the lasting margin of the stock to be lasted and for pulling said

lasting margin inwardly over the bottom of the shoe and in contact with said shoe-bottom-engaging means, during movement of said gripper in one direction, thereby to tension the stock in a direction normal to the bottom of the shoe and to draw its lasting margin inwardly over the shoe bottom, means operating in time relation to the pulling action of said gripper for pressing the lasting margin of the tensioned stock against the bottom of the shoe in a location closely adjacent to, but spaced lengthwise of the shoe from, said gripper, and means including a yieldably supported cam for causing said gripper to move in a path that is inclined first upwardly, away from the bottom of the shoe, and thereafter downwardly toward the shoe bottom, to augment the tensioning action of the gripper and to position the lasting margin of the tensioned stock close to the bottom of the shoe.

10. A lasting machine having, in combination, means for engaging the bottom of a shoe, a reciprocating gripper for seizing the lasting margin of the stock to be lasted and for pulling said lasting margin inwardly over the bottom of the shoe, during movement of said gripper in one direction, thereby to tension the stock in a direction normal to the bottom of the shoe and to draw its lasting margin inwardly over the shoe bottom, means for causing said gripper, when moving in the aforementioned direction, to follow a path that is inclined first upwardly, away from the bottom of the shoe, and thereafter downwardly toward the shoe bottom, to augment the tensioning action of the gripper and to position the lasting margin of the tensioned stock close to the bottom of the shoe, and means for rendering said last-mentioned means ineffective, thereby to cause the gripper to follow a path substantially parallel, and close to the bottom of the shoe, during movement in the opposite direction.

11. A lasting machine having, in combination, means for engaging the bottom of a shoe, a reciprocating gripper for seizing the lasting margin of the stock to be lasted and for pulling said lasting margin inwardly over the bottom of the shoe, during movement of said gripper in one direction, thereby to tension the stock in a direction normal to the bottom of the shoe and to draw its lasting margin inwardly over the shoe bottom, cam-operated means for causing said gripper, when moving in the aforementioned direction, to follow a path that is inclined first upwardly, away from the bottom of the shoe, and thereafter downwardly toward the shoe bottom to augment the tensioning action of the gripper and to position the lasting margin of the tensioned stock close to the bottom of the shoe, and means for rendering said cam-operated means ineffective, thereby to cause the gripper to follow a path substantially parallel, and close to the bottom of the shoe, during movement in the opposite direction.

12. A lasting machine having, in combination, means for engaging the bottom of a shoe, a reciprocating gripper for seizing the lasting margin of the stock to be lasted and for pulling said lasting margin inwardly over the bottom of the shoe, during movement of said gripper in one direction, thereby to tension the stock in a direction normal to the bottom of the shoe and to draw its lasting margin inwardly over the shoe bottom, means including a yieldably supported cam for causing said gripper, when moving in the aforementioned direction, to follow a path that is

inclined first upwardly, away from the bottom of the shoe, and thereafter downwardly toward the shoe bottom to augment the tensioning action of the gripper and to position the lasting margin of the tensioned stock close to the bottom of the shoe, and means for rendering said last-mentioned means ineffective, thereby to cause the gripper to follow a path substantially parallel, and close to the bottom of the shoe, during movement in the opposite direction.

13. A lasting machine having, in combination, means for engaging the bottom of a shoe adjacent to the marginal edge thereof, a reciprocating gripper for seizing the lasting margin of the stock to be lasted and for pulling said lasting margin inwardly over the bottom of the shoe and in contact with said shoe-bottom-engaging means, during movement of said gripper in one direction, thereby to tension the stock in a direction normal to the bottom of the shoe and to draw its lasting margin inwardly over the shoe bottom, means for causing said gripper, when moving in the aforementioned direction, to follow a path that is inclined first upwardly, away from the bottom of the shoe, and thereafter downwardly toward the shoe bottom, to augment the tensioning action of the gripper and to position the lasting margin of the tensioned stock close to the bottom of the shoe, and means for rendering said last-mentioned means ineffective thereby to cause the gripper to follow a path substantially parallel, and close to the bottom of the shoe, during movement in the opposite direction.

14. A lasting machine having, in combination, means for engaging the bottom of a shoe adjacent to the marginal edge thereof, a reciprocating gripper for seizing the lasting margin of the stock to be lasted and for pulling said lasting margin inwardly over the bottom of the shoe and in contact with said shoe-bottom-engaging means, during movement of said gripper in one direction, thereby to tension the stock in a direction normal to the bottom of the shoe and to draw its lasting margin inwardly over the shoe bottom, cam-operated means for causing said gripper, when moving in the aforementioned direction, to follow a path that is inclined first upwardly, away from the bottom of the shoe, and thereafter downwardly toward the shoe bottom to augment the tensioning action of the gripper and to position the lasting margin of the tensioned stock close to the bottom of the shoe, and means for rendering said cam-operated means ineffective, thereby to cause the gripper to follow a path substantially parallel, and close to the bottom of the shoe, during movement in the opposite direction.

15. A lasting machine having, in combination, means for engaging the bottom of a shoe adjacent to the marginal edge thereof, a reciprocating gripper for seizing the lasting margin of the stock to be lasted and for pulling said lasting margin inwardly over the bottom of the shoe and in contact with said shoe-bottom-engaging means, during movement of said gripper in one direction, thereby to tension the stock in a direction normal to the bottom of the shoe and to draw its lasting margin inwardly over the shoe bottom, means including a yieldably supported cam for causing said gripper, when moving in the aforementioned direction, to follow a path that is inclined first upwardly, away from the bottom of the shoe, and thereafter downwardly toward the shoe bottom to augment the tensioning action of the gripper and to position the lasting margin of the tensioned stock close to the bottom of the shoe.

shoe, and means for rendering said last mentioned means ineffective, thereby to cause the gripper to follow a path substantially parallel, and close to the bottom of the shoe, during movement in the opposite direction.

16. A lasting machine having, in combination, means for engaging the bottom of a shoe, a reciprocating gripper for seizing the lasting margin of the stock to be lasted and for pulling said lasting margin inwardly over the bottom of the shoe, during movement of said gripper in one direction, thereby to tension the stock in a direction normal to the bottom of the shoe and to draw its lasting margin inwardly over the shoe bottom, means operating in time relation to the pulling action of said gripper for pressing the lasting margin of the tensioned stock against the bottom of the shoe in a location closely adjacent to, but spaced lengthwise of the shoe from, said gripper, means for causing said gripper, when moving in the aforementioned direction, to follow a path that is inclined first upwardly, away from the bottom of the shoe, and thereafter downwardly toward the shoe bottom to augment the tensioning action of the gripper and to position the lasting margin of the tensioned stock close to the bottom of the shoe, and means for rendering said last-mentioned means ineffective, thereby to cause the gripper to follow a path substantially parallel, and close to the bottom of the shoe, during movement in the opposite direction.

17. A lasting machine having, in combination, means for engaging the bottom of a shoe, a reciprocating gripper for seizing the lasting margin of the stock to be lasted and for pulling said lasting margin inwardly over the bottom of the shoe, during movement of said gripper in one direction, thereby to tension the stock in a direction normal to the bottom of the shoe and to draw its lasting margin inwardly over the shoe bottom, means operating in time relation to the pulling action of said gripper for pressing the lasting margin of the tensioned stock against the bottom of the shoe in a location closely adjacent to, but spaced lengthwise of the shoe from, said gripper, cam-operated means for causing said gripper, when moving in the aforementioned direction, to follow a path that is inclined first upwardly, away from the bottom of the shoe, and thereafter downwardly toward the shoe bottom to augment the tensioning action of the gripper and to position the lasting margin of the tensioned stock close to the bottom of the shoe, and means for rendering the cam-operated means ineffective, thereby to cause the gripper to follow a path substantially parallel, and close to the bottom of the shoe, during movement in the opposite direction.

18. A lasting machine having, in combination, means for engaging the bottom of a shoe, a reciprocating gripper for seizing the lasting margin of the stock to be lasted and for pulling said lasting margin inwardly over the bottom of the shoe, during movement of said gripper in one direction, thereby to tension the stock in a direction normal to the bottom of the shoe and to draw its lasting margin inwardly over the shoe bottom, means operating in time relation to the pulling action of said gripper for pressing the lasting margin of the tensioned stock against the bottom of the shoe in a location closely adjacent to, but spaced lengthwise of the shoe from, said gripper, means including a yieldably supported cam for causing said gripper, when moving in the aforementioned direction, to follow a path that is inclined first

11

upwardly, away from the bottom of the shoe, and thereafter downwardly toward the shoe bottom to augment the tensioning action of the gripper and to position the lasting margin of the tensioned stock close to the bottom of the shoe, and means for rendering the last-mentioned means ineffective, thereby to cause the gripper to follow a path substantially parallel, and close to the bottom of the shoe during movement in the opposite direction.

19. A lasting machine having, in combination, means for engaging the bottom of a shoe adjacent to the marginal edge thereof, a reciprocating gripper for seizing the lasting margin of the stock to be lasted and for pulling said lasting margin inwardly over the bottom of the shoe and in contact with said shoe-bottom-engaging means, during movement of said gripper in one direction, thereby to tension the stock in a direction normal to the bottom of the shoe and to draw its lasting margin inwardly over the shoe bottom, means operating in time relation to the pulling action of said gripper for pressing the lasting margin of the tensioned stock against the bottom of the shoe in a location closely adjacent to, but spaced lengthwise of the shoe from, said gripper, means for causing said gripper, when moving in the aforementioned direction, to follow a path that is inclined first upwardly, away from the bottom of the shoe, and thereafter downwardly toward the shoe bottom to augment the tensioning action of the gripper and to position the lasting margin of the tensioned stock close to the bottom of the shoe, and means associated with said pressing means for rendering the last-mentioned means ineffective, thereby to cause the gripper to follow a path substantially parallel, and close to the bottom of the shoe, during movement in the opposite direction.

20. A lasting machine having, in combination, means for engaging the bottom of a shoe adjacent to the marginal edge thereof, a reciprocating gripper for seizing the lasting margin of the stock to be lasted and for pulling said lasting margin inwardly over the bottom of the shoe and in contact with said shoe-bottom-engaging means, during movement of said gripper in one direction, thereby to tension the stock in a direction normal to the bottom of the shoe and to draw its lasting margin inwardly over the shoe bottom, means operating in time relation to the pulling action of said gripper for pressing the lasting margin of the tensioned stock against the bottom of the shoe in a location closely adjacent to, but spaced lengthwise of

12

the shoe from, said gripper, cam-operated means for causing said gripper, when moving in the aforementioned direction, to follow a path that is inclined first upwardly, away from the bottom of the shoe, and thereafter downwardly toward the shoe bottom to augment the tensioning action of the gripper and to position the lasting margin of the tensioned stock close to the bottom of the shoe, and means associated with said pressing means for rendering the cam-operated means ineffective, thereby to cause the gripper to follow a path substantially parallel, and close to the bottom of the shoe, during movement in the opposite direction.

21. A lasting machine having, in combination, means for engaging the bottom of a shoe adjacent to the marginal edge thereof, a reciprocating gripper for seizing the lasting margin of the stock to be lasted and for pulling said lasting margin inwardly over the bottom of the shoe and in contact with said shoe-bottom-engaging means, during movement of said gripper in one direction, thereby to tension the stock in a direction normal to the bottom of the shoe and to draw its lasting margin inwardly over the shoe bottom, means operating in time relation to the pulling action of said gripper for pressing the lasting margin of the tensioned stock against the bottom of the shoe in a location closely adjacent to, but spaced lengthwise of the shoe from, said gripper, means including a yieldably supported cam for causing said gripper, when moving in the aforementioned direction, to follow a path that is inclined first upwardly, away from the bottom of the shoe, and thereafter downwardly toward the shoe bottom to augment the tensioning action of the gripper and to position the lasting margin of the tensioned stock close to the bottom of the shoe, and means associated with said pressing means for rendering the last-mentioned means ineffective, thereby to cause the gripper to follow a path substantially parallel, and close to the bottom of the shoe, during movement in the opposite direction.
